UNITED STATES PATENT OFFICE.

MARY E. KINTZ, OF LOS ANGELES, CALIFORNIA.

LINGERIE PIN.

Application filed April 11, 1927. Serial No. 182,767.

My invention relates to a lingerie pin and has for its principal objects the provision of a relatively simple, practical and inexpensive pin that is especially designed for engaging and holding in proper position the shoulder straps of lingerie; to provide a device of the character referred to that is formed from a single piece of material and which is provided with an internally arranged pin, which latter, when inserted through the shoulder portion of an outer garment, firmly secures the device in proper position upon the wearer; further, to provide a lingerie pin that may be easily and quickly manipulated when applied for use or detached from the garment; and, further, to provide a lingerie pin that is inexpensive of manufacture and which will be very effective in performing the functions for which it is intended.

With the foregoing and other objects in view, my invention consists in certain novel features of construction and arrangement of parts that will hereinafter be more fully described and claimed and illustrated in the accompanying drawing, in which—

Fig. 1 is a perspective view of a lingerie pin constructed in accordance with my invention.

Fig. 2 is an elevational view of the lingerie pin in closed position and with dotted lines showing a portion of the outer garment to which the pin is secured and also showing in dotted lines, portions of the engaged shoulder straps of lingerie.

Fig. 3 is an enlarged cross section taken on the line 3—3 of Fig. 2.

Fig. 4 is a perspective view of a modified form of the pin.

Fig. 5 is an elevational view, partly in section, of a further modified form of the pin.

Fig. 6 is a perspective view of a portion of a modified form of my improved lingerie clasp or pin.

In the construction of my improved lingerie pin, I utilize a narrow strip or band of relatively thin metal having a considerable degree of resiliency and said strip or band is bent at a point intermediate its ends to provide a pair of arms 10 and 11 that are substantially equal in length. That portion of the strip or band that is bent to form the two arms is rounded or formed so as to provide a substantially semi-circular bend 12 rather than an abrupt bend and thus the two arms may be sprung or flexed laterally rela-

tive to each other a sufficient distance to permit the free ends of the arms to pass each other.

The terminal portion of arm 11 is rebent inwardly, as designated by 13, so as to overlie the corresponding end of said arm 11, and formed integral with and projecting inwardly from the end of said terminal portion 13, is a pin or prong 14 having a pointed end. The under face of the upper end of arm 11 is roughened or provided with a series of short longitudinally disposed grooves 15.

The free end of arm 10 is rebent inwardly so as to provide a short underlying plate 16 and the upper face thereof is corrugated or provided with a series of short longitudinally disposed ribs 17 that are adapted to engage in the grooves 15 when the free end of arm 10 is positioned over the free end of arm 11.

Formed integral with and projecting upwardly from the intermediate portion of arm 10, is a short lip or flange 18 that may be engaged by the thumb or finger when the resilient arms of the pin are manipulated to secure or fasten the pin and likewise to unfasten the same.

In Fig. 4, I have shown a modified construction wherein the two arms forming the pin, instead of being integrally connected or formed in a single piece, are flexibly connected to each other at one end by means of a hinge joint, the same consisting of a loop 19 formed on one arm and which loop fits loosely through a slot or aperture 20 in the corresponding end of the other arm. This hinge joint is formed so as to permit the free ends of the arms to be moved sidewise a sufficient distance to enable the same to pass one another when the pin is fastened or unfastened.

In the modified construction illustrated in Fig. 5 the resilient arms of the pin are provided at intermediate points with inwardly pressed indentations or perforations, the inner ends of which provide roughened surfaces that tend to grip the portions of the garment that are engaged between the arms of the pin when the same is in service.

In the use of my improved lingerie pin, the same is positioned on the inside of the shoulder portion of an outer garment and the pin or prong 14 is inserted through a portion of said outer garment, preferably the shoulder seam, or the inwardly project-

ing portions of the garment adjacent to said seam and, after the shoulder straps of the lingerie have been positioned between the arms, the free ends of which are spread apart, the ends of said arms are moved laterally in opposite directions so that the same may pass each other and said ends are now moved toward each other until the end of arm 10 and the in-turned plate 16 thereof is positioned upon and around the end of arm 11 and the in-turned portion 13 thereof.

When the ends of the pin have been thus sprung or snapped together, the ribs or roughened face of plate 18 engage in the grooves or roughened face of the free end of arm 11, thus tending to lock the free ends of the pin in engagement with each other.

Thus the pin is firmly secured to the shoulder portion of an outer garment and said pin, when closed, provides a loop that receives and retains in proper position on the shoulder of the wearer, the shoulder straps of lingerie.

In the modified form of the device illustrated in Fig. 6, a keeper 14^a in the form of a lip that is pressed up or inwardly from the member 11 is utilized for retaining the end of the pin or prong 14 after the same has been inserted through a portion of the clothing and thus the clasp may be positively secured to the clothing.

A lingerie pin of my improved construction is comparatively simple, is inexpensive of manufacture, capable of being easily and quickly applied for use or detached from the garment to which it is secured and provides an efficient and convenient retainer for the shoulder straps of undergarments and the like.

It will be understood that minor changes in the size, form and construction of the various parts of my improved lingerie pin may be made and substituted for those herein shown and described without departing from the spirit of my invention, the scope of which is set forth in the appended claims.

I claim as my invention:

1. A lingerie pin comprising a pair of

spaced arms connected at one end, a pin formed integral with the free end of one of said arms and projecting into the space between said arms and an interned hook on the end of the other arm, which hook is adapted to engage over the end of the arm having the inwardly projecting pin. 55

2. A lingerie pin comprising a pair of arms connected at one end and normally spaced apart, means on the free ends of said arms for retaining the same in closed position and a pin formed integral with the free end of one of said arms and projecting lengthwise through the space between said arms. 60

3. A lingerie pin comprising a pair of relatively narrow strips of resilient metal connected at one end, an inwardly projecting prong formed integral with the free end of one of said arms and an inwardly projecting hook formed on the end of the other arm and adapted to engage around the end 70 of the arm having the inwardly projecting hook.

4. A lingerie clasp comprising a pair of resilient arms connected at one end and normally spaced apart and a pin projecting 75 inwardly from the free end of one of said arms so as to occupy a position between said arms.

5. A lingerie clasp comprising a pair of resilient arms connected at one end and normally spaced apart, a pin projecting inwardly from the free end of one of said arms so as to occupy a position between said arms and a keeper beneath which the free end of said pin may be engaged. 85

6. A lingerie clasp comprising a pair of resilient arms connected at one end and normally spaced apart, a pin projecting inwardly from the free end of one of said arms so as to occupy a position between said arms, a keeper beneath which the free end of said pin may be engaged and means on the free ends of said arms for retaining the same in closed position. 90

In testimony whereof I affix my signature.

MARY E. KINTZ.
